UNITED STATES PATENT OFFICE.

EDGAR S. HARPST, OF TYLER, TEXAS.

MECHANICAL MOTOR.

SPECIFICATION forming part of Letters Patent No. 406,440, dated July 9, 1889.

Application filed March 11, 1889. Serial No. 302,864. (No model.)

To all whom it may concern:

Be it known that I, EDGAR S. HARPST, a citizen of the United States, residing at Tyler, in the county of Smith and State of Texas, have invented certain new and useful Improvements in Mechanical Motors; and I do hereby declare the following to be a full, clear, and exact description of the invention, such as will enable others skilled in the art to which it appertains to make and use the same.

The invention relates to mechanical motors; and it consists in the construction and novel combinations of parts, as hereinafter described, illustrated in the accompanying drawings, and pointed out in the appended claim.

The object of my invention is to provide a motor of cheap and simple construction, which is adapted for driving various classes of light machinery, and more especially for use in connection with fans, such as are commonly used for creating currents of air in bar-rooms, dining-rooms, and the like.

In the accompanying drawings, Figure 1 is a side view of my improved motor as applied to a fan-frame; Fig. 2, an end view of the same.

In the above drawings, A designates the ceiling of a room, and B one of the side walls.

In constructing my motor it is my object to so arrange the parts thereof that the weight employed will be suspended from the ceiling of the room, instead of some temporary structure located between the floor and the ceiling, whereby the weight will have a greater range of movement, and thus serve to keep the motor in operation for a longer period of time before it becomes necessary to rewind the operating-rope, and the above object I attain by the arrangement now to be described.

Secured to the side wall B of the room, at a suitable point intermediate the floor and ceiling, is a suitable frame C, which is provided with the upper and lower forwardly-projecting arms c c'. Journalled in bearings in the outer ends of the arms c' is a shaft D, upon which is rigidly mounted a drum E, grooved, as shown, for the reception of the coils of a rope F, which serves to support the weight presently described, the flange e of the drum being provided with ratchet-teeth, as shown.

Upon one end of the shaft D is loosely

mounted a gear-wheel G, the latter being provided with a pawl g, which engages with the teeth on the flange e.

Journalled in bearings in the outer ends of the arms c is a shaft H, carrying at one end a pinion I, which meshes with the gear-wheel G on the shaft D, as shown.

For imparting the motive power to the parts just described, I employ a weight M, suspended from the cord or rope F by means of the hook n, which passes through an eye in the weight. One end of the cord or rope F is attached to the winding-drum E. It then passes over pulley O, supported in hanger o, secured to the ceiling, then around a pulley m, carried by the weight, and is secured at its other end to a hook o', attached to the ceiling. It will be seen that by thus suspending the weight the range of movement of the same is equivalent to the height of the room in which the motor is located.

In order to impart an oscillatory movement to the fan-frame, I employ the following means: Upon the shaft H is mounted a wheel K, which is provided with a cam-shaped recess k of the contour shown. Upon an arm of the frame C is pivoted one end of an oscillating rod S, which is provided with an anti-friction roller which rides in the cam-shaped recess k in the wheel K, the other end of the rod being pivoted to one end of a connecting-rod T, the other end of the latter being provided with a suitable eye or opening for attaching it to a fan-frame or the like.

The operation of my device will be readily understood from the foregoing description, taken in connection with the accompanying drawings, and need not be set forth in detail.

What I claim is—

The combination of the supporting-frame C, provided with the forwardly-projecting arms c c', the shaft D, having its bearings in the arms c', the drum E, loosely mounted on said shaft, and the gear-wheel G, rigidly mounted on said shaft intermediate said arms c', said drum E being provided with a toothed flange e, a pawl g, pivoted to said gear-wheel and engaging the teeth of said flange, the shaft H, having its bearings in the arms c, carrying at one end the pinion I, which meshes with the gear-wheel G, and at its other end the wheel

K upon the outside of one of the arms *c*, said wheel K being provided upon its outer face with the cam-shaped recess *k*, the rod S, pivoted to the frame and carrying intermediate 5 its ends the anti-friction roller traveling in said recess, the connecting-rod T, adapted to be connected at one end to a fan-frame, its opposite end being pivoted to the upper end of the rod S, the rope F, attached at one end 10 to the drum E, passing over a pulley attached

to the ceiling and attached at its opposite end to the ceiling, and the weight M, carried by said rope, substantially as specified.

In testimony whereof I affix my signature in presence of two witnesses.

EDGAR S. HARPST.

Witnesses:

JEFF. D. BURNS,
H. H. ROWLAND.

It is hereby certified that in Letters Patent No. 406,440, granted July 9, 1889, upon the application of Edgar S. Harpst, of Tyler, Texas, for an improvement in "Mechanical Motors," errors appear in the printed specification requiring the following corrections, viz: In line 45, page 1, the word "rigidly" should read *loosely*; and in line 51, same page, the word "loosely" should read *rigidly*; and that the Letters Patent should be read with these corrections therein that the same may conform to the record of the case in the Patent Office.

Signed, countersigned, and sealed this 30th day of July, A. D. 1889.

[SEAL.]

Countersigned:

C. E. MITCHELL,

Commissioner of Patents.

CYRUS BUSSEY,

Assistant Secretary of the Interior.
